UNITED STATES PATENT OFFICE.

FREDERICK L. ROBINSON AND JOHN McCABE, OF CHEYENNE, WYOMING, ASSIGNORS TO THE WYOMING TRACK SAND CO., OF CHEYENNE, WYOMING.

TRACK-SANDING APPARATUS.

No. 910,726.

Specification of Letters Patent.

Patented Jan. 26, 1909.

Application filed July 28, 1908. Serial No. 445,704.

To all whom it may concern:

Be it known that we, FREDERICK L. ROBINSON and JOHN McCABE, citizens of the United States, residing at Cheyenne, in the county of Laramie and State of Wyoming, have invented a new and useful Track-Sanding Apparatus, of which the following is a specification.

This invention relates to track sanding apparatus for locomotives and more particularly to sanders of the type disclosed in Patent No. 844,618, dated February 19, 1907. In mechanisms of this character where sand can be delivered in rear as well as in advance of the driving wheels, it will be understood that the rear sander is seldom used, and then only in an emergency. As a consequence, sand becomes packed therein, and this particular part of the apparatus is apt to become inoperative for that reason.

One of the principal objects of the present invention is to construct the mechanism so that fresh sand is constantly fed to both the rear and forward sanders whenever the latter is used, thus avoiding the objection noted.

A further and important object is to provide a simple form of air nozzle from which the sand is effectively excluded without interfering with the supply of air, said nozzle moreover being of a character that will permit its being cleansed without the necessity of dismantling the air connection.

The preferred embodiment of the invention is illustrated in the accompanying drawings, wherein:—

Figure 1 is a side elevation of a locomotive with the apparatus in place thereon. Fig. 2 is a form in elevation on an enlarged scale of a portion of the mechanism. Fig. 3 is a longitudinal sectional view therethrough on an enlarged scale. Fig. 4 is a detail sectional view on the line 4—4 of Fig. 3.

Similar reference numerals designate corresponding parts in all the figures of the drawings.

In the embodiment illustrated, the locomotive, which is designated by the reference numeral 5 is provided with the usual driving wheels 6 and with a reservoir or sand box 7. From this reservoir on each side, leads a single sand conduit 8, the lower portion of which is in the form of a casing 9 having its bottom closed by a detachable plug 10. Leading from one side of the upper portion of

the casing 9 is a sand-conducting pipe 11 that has its discharge end disposed in rear of one of the driving wheels 6. Leading from the opposite side of the casing 9 and at a lower point, is another sand-conducting pipe 12 that delivers in advance of one of the driving wheels 6, as will be evident by reference to Fig. 1. Air or motive fluid supply pipes 13, extending from the cab of the locomotive and provided in said cab with any suitable controlling means, are connected to nozzles 14 and 15. These pipes furthermore have branches 16 extending over the locomotive to the sanding apparatus on the opposite side, as will be evident by reference to Fig. 1.

Each of the nozzles 14 and 15 comprises a tapered body 17 having a portion threaded as shown at 18 into one side of the casing 9. Thus in the present embodiment the nozzle 14 is located opposite to the inlet end of the pipe 11 and in line therewith, while the nozzle 15 is arranged opposite to and in line with the inlet end of the pipe 12. Jam nuts 19, threaded on to the nozzles, abut against the sides of the casing to securely maintain the nozzles in position. It will be noted that each nozzle is provided with a longitudinal bore 20 extending entirely through the same and an inclined lateral supply port 21 communicates with this bore between its ends.

The pipes 13 are in communication with the ports 21. Inasmuch as the inner ends 22 of the nozzles extend across the casing, enter the inlet ends of the pipes 11 and 12, and are of less cross sectional area than said pipes, it will be evident that air supplied through these nozzles will be projected longitudinally 90 into the inlet ends of said pipes, and, forming partial vacuums in the casing, will cause the sand to be drawn into the pipes and delivered either in advance of or behind the wheels. 95

The outer ends of the bores 20 are closed by plugs 23, and carried by the inner ends of these plugs are stems 24 that extend longitudinally through the bore, being of less cross sectional area than the same and spaced 100 from the walls of the bores. In the lateral ports 21 are turning valves 25 having intersecting ports 26 and 27 of different diameters.

These valves are fully covered by the prior patent, to which reference has already been 105 made.

Particular attention is called to the fact that the pipe 12, which conveys sand to a

point in advance of the drivers, is located lower than the pipe 11. As already stated the forward sander is used much more than the rear sander, and it will be evident that in 5 this construction all the sand, which is passed through said forward sander, or in other words, through the pipe 12, must pass through the upper portion of the casing, and consequently past the rear sander 11. There 10 is therefore no chance of the sand becoming packed in the rear sander, and the latter is always ready for use.

It will be evident by reference to Fig. 3 that this structure is very simple, and there 15 are decided advantages for the particular form of nozzle employed. In the first place, the stem 24 excludes grains of sand from entering the nozzle, and the valve 25, being located above the bore, is completely protected from the dirt. However, should it become necessary to cleanse the bore, the plug 23 and stem 24 can be readily removed without dismantling the connection of the pipe 13 with the nozzle.

20 25 From the foregoing, it is thought that the construction, operation and many advantages of the herein described invention, will be apparent to those skilled in the art, without further description, and it will be understood that various changes in the size, shape, proportion, and minor details of construction may be resorted to without departing from the spirit or sacrificing any of the advantages 30 35 of the invention.

35 Having thus fully described our invention, what we claim as new, and desire to secure by Letters Patent, is:—

1. The combination with a locomotive having driving wheels, of a sand reservoir 40 mounted on the locomotive, a sand conduit leading from the reservoir and having a closed lower end, a sand conducting pipe leading from one side of the conduit and delivering in rear of one of the driving wheels, 45 means for directing motive fluid under pressure into said pipe, another sand conducting pipe leading from the opposite side of the conduit below the first pipe and delivering in front of one of the driving wheels, and means 50 for directing motive fluid longitudinally into the last mentioned pipe.

2. The combination with a locomotive having driving wheels, of a sand reservoir mounted on the locomotive, a sand conduit 55 leading from the reservoir, a sand-receiving casing forming the lower end of the conduit and having a closed bottom, a sand conducting pipe leading from one side of the casing and delivering in rear of one of the driving 60 wheels, a nozzle connected to the opposite side of the casing for directing motive fluid under pressure into the inlet end of the pipe, another sand conducting pipe leading from the same side of the casing as the nozzle and delivering 65 in front of one of the driving wheels, said

latter pipe having its inlet end lower than the first mentioned pipe, and a nozzle connected to the casing opposite to the inlet end of the second conducting pipe for directing motive fluid thereinto.

70

3. In a track sanding device, the combination with a casing, of means for delivering sand thereinto, a sand conducting pipe leading from one side of the casing, a nozzle connected to the other side of the casing in line 75 with the pipe, said nozzle having a longitudinal bore opening through both ends, and a lateral supply port communicating with the bore between its ends, a detachable closure for the outer end of the bore, and a motive fluid supply pipe connected to the supply port.

4. In a track sanding device, the combination with a casing, of means for delivering sand thereinto, a sand conducting pipe leading from one side of the casing, a nozzle connected to the other side of the casing in line 80 with the pipe, said nozzle having a longitudinal bore opening through the inner end and a lateral supply port communicating with the bore between its ends, a controlling valve located in the lateral port, and means for supplying motive fluid to the port.

5. In a track sanding device, the combination with a casing, of means for delivering sand thereinto, a sand conducting pipe leading from one side of the casing, a nozzle connected to the other side of the casing in line with the pipe, said nozzle having a longitudinal bore opening through both ends, and a lateral supply port communicating with the bore between its ends, a detachable closure for the outer end of the bore, a controlling valve located in the lateral port, and a motive fluid supply pipe connected to said lateral port.

95

6. In a track sanding device, the combination with a casing, of means for delivering sand thereinto, a sand conducting pipe leading from one side of the casing, a nozzle connected to the other side of the casing in line with the pipe, said nozzle having a longitudinal bore opening through both ends, and a lateral supply port communicating with the bore between its ends, and a detachable closure for the outer end of the bore having a stem detachably extending into said bore and of less cross-sectional area than the same, said stem being detachable with the closure.

100

7. In a track sanding device, the combination with a casing, of means for delivering sand thereinto, a sand conducting pipe leading from one side of the casing, a nozzle projecting through the other side of the casing in line with the pipe, said nozzle having a longitudinal bore opening through both ends and a lateral supply port communicating with the bore between its ends, a closure plug threaded into the outer end of the bore, and a stem carried by the inner end of the plug 115 120 125 130

and projecting longitudinally through the bore, said stem being of less cross sectional area than the bore.

8. The combination with a locomotive having driving wheels, of a reservoir for sand mounted on the locomotive, a sand conduit leading from the reservoir and having a closed lower end, an upper sand conducting pipe leading from one side of the conduit and 10 delivering in rear of one of the driving wheels, a lower sand conducting pipe having its inlet end connected to the casing below the first mentioned pipe and delivering in advance of one of the driving wheels, oppositely extending nozzles threaded into the casing in line with the inlet ends of the sand conducting pipes, each nozzle having a longitudinal bore and an inclined supply port communicating with the bore between its

ends, a motive fluid supply pipe connected to 20 the supply port of each nozzle, a turning valve located in each nozzle and operating across the supply port thereof, a closure plug detachably threaded into the outer end of the bore of each nozzle, and a stem fixed to 25 the inner end of each closure plug and extending longitudinally within the bore, said stem being of less cross sectional area than the bore.

In testimony, that we claim the foregoing 30 as our own, we have hereto affixed our signatures in the presence of two witnesses.

FREDERICK L. ROBINSON.
JOHN McCABE.
